UNITED STATES PATENT OFFICE.

WILLIAM J. ADAMS, JR., OF NEW YORK, N. Y., ASSIGNOR TO WESTERN ELECTRIC COMPANY, INCORPORATED, OF NEW YORK, N. Y., A CORPORATION OF NEW YORK.

ELECTRIC-CURRENT TRANSMISSION.

Application filed September 10, 1924. Serial No. 736,835.

- This invention relates to transmission of electric currents and aims to provide a flexible line of propagation for them without unduly shunting current across the line of propagation and without permitting undue interference from extraneous electrical fields. An especial object is to avoid such undue shunting effect and interference where the flexible line of propagation comprises a connection between impedances which are high for alternating currents to be transmitted, as for instance a connection between a condenser transmitter and an electron discharge amplifier.
- 15 In accordance with the invention, for connecting the impedances between which current is to be transmitted there is provided a flexible electrical cord comprising two electrical conductors, one of which is arranged to shield the other from extraneous electrical fields, and insulating means maintaining the capacity and leakage resistance of the cord at such values as to substantially avoid deleteriously shunting the currents to be transmitted.
- 20 The single figure of the drawing shows one embodiment of the invention, with parts of the cord shown broken away to exhibit its internal structure.
- 25 In the drawing the cord 2 is shown connecting a condenser transmitter 3 to an electron tube amplifier 4. The space current battery 9 for the first stage of the amplifier is shown as supplying polarizing potential for the condenser transmitter through a resistance 10 which may be of the order of 15 megohms. A resistance 11, which may be of the order of two megohms, and capacities 12 and 13, which may be of the order of two microfarads form a filter to prevent fluctuations of the voltage of battery 9 from affecting the transmitter 3.
- 30 The condenser transmitter 3 may be a telephone transmitter having a capacity, for example of the order of 400 micromicrofarads. Its impedance at speech frequencies will then be very high, and therefore it is shown connected directly to the grid of the input stage of the amplifier through a suitable blocking condenser 15 without the interposition of a transformer. A resistance 16 which may be of the order of 15 megohms, is connected across the grid and filament of the first stage of the amplifier, to maintain the grid at a constant negative average potential.
- 35 Any capacity between the conductors of the cord connecting the transmitter to the amplifier is in shunt with the transmitter, with respect to the amplifier, and therefore occasions transmission loss. On account of the relatively low capacity of the transmitter itself, this loss, when ordinary flexible cords of any considerable length are used, is quite large. The flexible cord 2 is therefore constructed, as described herein-after, to have low capacity between its conductors. Moreover, unless proper shielding is employed, the deleterious effect of any inductive interference to which the conductors of the cord connecting the transmitter to the amplifier are subjected, due to extraneous electrical fields, may be pronounced because of the low magnitude of the voltages delivered to the input of the amplifier by the transmitter. Therefore, the flexible cord 2 is constructed, as described, herein-after, with two concentric conductors, one of which shields the other. Further, as also described herein-after, rubber or other insulating material impervious to moisture and having high insulation resistance, is preferably interposed between the inner conductor and the outer conductor, to afford high insulation resistance and to prevent moisture from setting up irregular leakage paths which would result in excessive noise currents. However, the thickness of the interposed rubber should be as small as is consistent with the attainment of the requisite insulation resistance, so that the rubber, which has high specific inductive capacity, will not unduly increase the capacity between the conductors.
- 40 The center of the cord 2 is a flexible conductor 20, preferably consisting of a plurality of conducting strands of tinsel thread. These strands are not individually shown, since they are of general type of construction referred to in U. S. patents to Sawyer 269,328, December 19, 1882 and Reed 286,963, October 16, 1883, each strand or tinsel thread being a thread of fibrous material wound helically with metallic tape. These strands are twisted together to form conductor 20, which is then served with two layers of floss or a similar insulating material 21, these layers being laid with the direction of winding reversed. Over these servings is placed an insulating coating 22 of soft rubber, which, as indicated above, should be as

thin as is consistent with the attainment of the insulation resistance which it must provide. Over the rubber is provided a flexible fibrous insulating covering 23, preferably of 5 silk braiding, the rubber 22 and the braiding 23 extending substantially to the ends of conductor 20.

Over the braiding 23 are applied three flexible fibrous insulating coverings, 24, 25 10 and 26, preferably of silk braidings, each extending between the points at which the free conductors of the cord 2 are to emerge from the finished cord, and being discontinued at those points.

15 Over the braiding 26 is applied a flexible conducting and shielding braiding 27, preferably of gold tinsel thread, this braiding 27 terminating in a free, closely braided conductor at each end.

20 Over the tinsel braiding 27 is applied a flexible fibrous insulating covering 28, preferably of silk braiding, extending out over the bare tinsel braided free conductors formed by the ends of the braiding 27.

25 Over the braiding 28 is applied a flexible insulating braiding 29, preferably of silk, terminated in a whipping 30 of silk, shelled, at the amplifier end of the cord, and, at the other end, extended out over the 30 braiding 28 as indicated in the drawing, or, if desired, at the latter end, closely braided and brought off from the cord as a stay cord or tie cord, from the point where the free conductors emerge from the cord, for 35 instance, in the fashion shown in U. S. patent to Kaisling 738,545, September 8, 1903.

The capacity between the conductors of the cord preferably should not exceed about 40 50 micromicrofarads per linear foot. Moreover, the cord should be as short as is consistent with convenience. A length of about ten feet has been found suitable in a circuit of the type shown in the drawing.

What is claimed is:

45 1. In combination, a condenser subject to variations of its capacity, corresponding to sound waves, and an electrically conductive cord, said cord comprising electrically conductive means connected to one electrode 50 of said condenser, an electrically conductive casing connected to another electrode of said condenser and encasing said means, and insulating means spacing said conductive means from said conductive casing sufficient-

ly to render the electrostatic capacity between said conductive means and said casing small relative to the variations to which the capacity of said condenser is subject. 65

2. In combination, a condenser type telephone instrument and a cord for connecting 60 said instrument in a circuit, said cord comprising a flexible center conductor, a flexible conductive shield serving as a return conductor, and flexible insulating material separating said center conductor from said shield sufficiently to render the capacity of 65 said cord low compared to that of said transmitter.

3. In combination, a condenser transmitter and a cord for connecting said instrument in a circuit, said cord comprising a flexible center conductor and a braided tinsel shield sufficiently separated by flexible insulating material to render the capacity 70 between said conductor and said shield small, compared to that of said transmitter. 75

4. In combination, a condenser transmitter and a cord for connecting said instrument in a circuit, said cord comprising a rubber covered, tinsel, center conductor and a braided tinsel shield sufficiently separated by a plurality of layers of insulating braid 80 to render the capacity of said cord small compared to that of said transmitter.

5. In combination, a condenser transmitter, an electron discharge device having electrodes, and a cord connecting said transmitter to said electrodes, said cord comprising a flexible center conductor and a flexible conductive shield separated by a plurality 85 of layers of flexible insulation maintaining the capacity and leakage resistance of the cord at such values as to substantially avoid deleteriously shunting the circuit between said transmitter and said electrodes. 90 95

6. In combination, an electron discharge device having two input electrodes one of which is grounded, a condenser transmitter, and means for connecting the terminals of said transmitter to said electrodes comprising a conductor surrounded by a conductive shield and insulated therefrom, said shield serving as the circuit conductor to said grounded electrode. 100

In testimony whereof, I hereunto subscribe my name this 8 day of September A. D. 1924.

WILLIAM J. ADAMS, JR.
